UNITED STATES PATENT OFFICE

173,150

LENS PANEL FOR DIRECT LIGHTING FIXTURES

Kurt Franck, Newark, Ohio, assignor to Holophane Company, Inc., New York, N. Y., a corporation of Delaware

Application August 11, 1953, Serial No. 26,399

Term of patent 14 years

(Cl. D48—23)

To all whom it may concern:

Be it known that I, Kurt Franck, a citizen of the United States of America and a resident of Newark, county of Licking, State of Ohio, have invented a new, original, and ornamental Design for a Lens Panel for Direct Lighting Fixtures, of which the following is a specification, reference being had to the accompanying drawings, forming a part thereof.

In the drawings:

Figure 1 is a bottom plan view of a lens panel for direct lighting fixtures, showing my new design;

Fig. 2 is a fragmentary cross sectional view to a larger scale taken on line 2—2 of Fig. 1; and

Fig. 3 is a fragmentary cross sectional view to a larger scale taken on line 3—3 of Fig. 1.

The design forming the subject-matter of the present invention is for a lens panel for direct lighting fixtures, the panel being of arbitrary over-all length and width.

I claim:

The ornamental design for a lens panel for direct lighting fixtures, as shown and described.
